(57) **CLAIM**

The ornamental design for a camera equipped network door station, as shown and described.

DESCRIPTION

FIG. 1 is a front perspective view of a first embodiment of a camera equipped network door station in accordance with our design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a top plan view thereof;

FIG. 8 is a front perspective view of a second embodiment of a camera equipped network door station in accordance with our design;

FIG. 9 is a right side elevational view thereof;

FIG. 10 is a front elevational view thereof;

FIG. 11 is a left side elevational view thereof;

FIG. 12 is a rear elevational view thereof;

FIG. 13 is a bottom plan view thereof; and,

FIG. 14 is a top plan view thereof.

The broken lines depict portions of the camera equipped network door station in which the design is embodied that form no part of the claimed design.

1 Claim, 9 Drawing Sheets
